FIG. 2.

FIG. 4.

UNITED STATES PATENT OFFICE

2,033,267

BARREL

Charles H. Widman, Detroit, Mich., assignor to
The Murray Corporation of America, a corpora-
tion of Delaware

Application April 8, 1933, Serial No. 665,139

4 Claims. (Cl. 220—68)

My invention relates to barrels and particularly to a barrel of the all-metal type made up of similar preformed sections which are welded together to form a complete barrel.

5 Tight barrels which are employed by wine and cider makers, brewers and distillers have usually been made of wood, preferably of well seasoned oak in the shape of staves which were preformed to provide a bilge to the barrel, that is to say, the
10 bulge or enlargement at its central portion. The staves were preformed to accurately mate with each other throughout their lengths. The staves were assembled together by hoops, the ends were beveled and a groove was provided near the end
15 in which heads were fitted to form the complete barrel. This operation required a considerable amount of time, skilled labor and was expensive.

In practicing my invention, I construct a tight barrel entirely of metal, formed of like stampings
20 which are so fabricated as to readily mate with each other and be welded or otherwise secured together to form a complete barrel which is reinforced at the parts desiring added strength. The reinforcing is so constructed as to provide rings
25 on which the barrel may be rolled to follow a straight path.

Accordingly, the main objects of my invention are: to construct a barrel of the tight type which
30 is made entirely of metal; to form two like stampings of conoidal shape which, when mated together, form a complete barrel having a bulge in the center and heads on both ends; to provide reinforcing end caps for the barrel portion so formed, with projection portions near their ends
35 as to extend beyond the bulge of the barrel portion, to press fit the reinforcing end caps over the ends of the barrel portion and weld or otherwise secure them permanently thereto; to provide
40 flanged apertures in the barrel portion to which collars are welded or otherwise secured to form bungs for the barrel and, in general, to fabricate a barrel from preformed metal elements which is rigid in construction, which is leak proof and
45 which is economical of manufacture.

Other objects and features of novelty of my invention will be either specifically pointed out or will become apparent when referring, for a better understanding of my invention, to the following
50 description taken in conjunction with the accompanying drawing, wherein:

Figure 1 is a broken plan view, partly in section, of a barrel embodying features of my invention.
Fig. 2 is a sectional view of the structure illus-
55 trated in Fig. 1, taken on the line 2—2 thereof,

Fig. 3 is an exploded view, in section, of one-half of the barrel illustrated in Fig. 1.

Fig. 4 is a broken sectional view of a barrel, similar to that illustrated in Fig. 1, showing a modified form thereof, and

Fig. 5 is a broken sectional view of a barrel, similar to that illustrated in Fig. 4, showing a further modified form thereof.

I have illustrated, in Figs. 1, 2 and 3, a barrel
10 which is fabricated from like sheet metal
stampings. The barrel referred to is constructed
in the main, of two similar conoidal elements 11,
which are of pot-shape, having outwardly diverg-
ing sides 12 and bottoms 13. The edges are out-
wardly flanged at 14 and are abutted to each
15 other and welded, preferably by a butt welding
operation, to form a tight joint. It is to be under-
stood that brazing, torch or electric welding may
be employed instead of the butt weld, or any
20 other well known method in the art may be uti-
lized. Two apertures are provided in the barrel
portion so formed, the aperture 15 in one of the
bottoms 13, having a flange 16 thereabout, more
clearly illustrated in Fig. 3. A semi-circular ap-
erture 17 is provided in each half 11 of the
25 pressed metal portion, having a semi-circular
flange 18 thereabout which forms a complete ap-
erture when the two halves 11 are welded to-
gether. A collar 19, having a shoulder 21 therein,
30 projects over the flange 18 of the aperture 17 in
the side of the barrel portion. The collar is pref-
erably made of cast iron or other rust resisting
metal and is welded, brazed or otherwise secured
to the flange 18.

Reinforcing elements 22 are formed from sheet
metal to encompass the end portions 11 of the
barrel, being provided with a pressed-in head
portion 23, downwardly projecting side portions
24 and outwardly pressed annular portions 25
which form rings which project beyond the bulge
and the collar 19 of the barrel to permit the roll
of the barrel in a straight direction. The up-
wardly projecting marginal portion 26 of the re-
inforcing member 22 forms a handhold for the
barrel by which it may be lifted and carried and
provides edges upon which the barrel may be
stood or stacked, one upon the other. The rein-
forcing member 22 is pressed upon the outer
surface of the portion 11 of the barrel and is
thereafter welded or otherwise secured thereto.

The member 22 is not only spot-welded along
the portion 24 but is preferably continuously
welded at the edge of the member, between the
rings 25 and the central portion of the barrel,

to prevent moisture and refuse from entering the space between the inner surface of the ring 25 and the outer surface of the element 11.

It is to be understood that the head 23 may be 5 cut out or omitted and a flange provided in its stead, which is likewise continuously welded to the head 13 of the barrel to form a water tight joint.

An aperture 27 is provided in the head 23 10 through which projects a collar 28 having a shoulder 29 for receiving the flange 16 of the aperture 15. The collar 28 is brazed, welded or otherwise secured to the flange and to the marginal edge of the aperture 27. It is to be understood 15 that the aperture 27 is only provided in the reinforcing member 22 which is to go over the end 11 of the barrel in which the aperture 15 is provided.

The barrel, so reinforced, is sturdy of construction 20 and will stand considerable abuse in use and shipment. In view of the metal construction, the barrel will not leak, warp or decay, as in the case of the wooden barrel, and its life of usefulness is materially increased thereover. It will be noted 25 that only two sets of dies will be necessary to form the barrel elements, one for forming the elements 11 and the other for forming the reinforcing members 22. The only difference to be found in the two elements 11 is the aperture 15 30 provided in one of the elements which may be formed by a separate operation. For this reason, the tools for constructing such a barrel are retained at a minimum in number and cost.

In Fig. 4, I have shown a modified form of reinforcing elements 31 which are provided with an outwardly curved flange portion 32 which follows the curve of the end of the barrel portion 11. The terminal ends 33 of the elements 31 are rolled about annular rods 34 to provide the rings upon 40 which the barrel rolls. Upwardly directed flanges 35 on the elements 31 provide the terminals for the barrel by which it is carried and upon which it is stood or stacked. The terminal ends 36 of the flanges 31 are likewise rolled about annular rods 37. The elements 31 are pressed upon the ends of the barrel portions 11 and are welded, 45 brazed or otherwise permanently secured thereto.

In Fig. 5, I have shown a further modified form 50 of barrel, wherein the barrel portions 41 are shouldered at 42 to provide additional strength to the heads 13. The shoulders 42 are engaged by upstanding portions 43 of reinforcing members 44 which are secured thereto. The upstanding portions 43 are provided with the terminal ends 55 36 which are bent around the annular rods 37, as in the modified form illustrated in Fig. 4. The portions 43 are provided with apertured portions 45, the metal 46 thereof being bent inwardly to provide handholds by which the barrel, when of 60 small size, may be lifted directly at one end. Below the upstanding flange portions 43 the reinforcing members 44 are curved at 47 to follow the curve of the barrel portions 41, the terminal end 33 thereof being bent around an annular rod 34, as in the modified form illustrated in Fig. 4. The element 44 is pressed upon the end of the 65

barrel, into firm, tight engagement therewith, and is welded, brazed or otherwise secured directly thereto.

The barrel thus constructed is simple of manufacture, requiring no skilled operators, and is of exact capacity, since all of the elements thereof are stamped from the same dies. The rings provided on the side of the barrel protects the bung and permits the barrel to be rolled in a straight line. The projecting end portions or chimes provide handholds and terminal ends upon which the barrels may be stood or stacked, as the case may be. The reinforcing ends are press fitted 10 on the ends of the barrel portion and are welded or otherwise secured in place to materially reinforce the metal of the barrel portion. The barrel thus constructed will stand considerable abuse 15 and has an exceedingly long life.

While I have described and illustrated but a single embodiment of my invention, it will be 20 apparent to those skilled in the art that various changes, omissions, additions and substitutions may be made therein without departing from the spirit and scope of my invention, as set forth in the accompanying claims.

I claim as my invention:

1. A barrel made of two like sheet metal flanged elements which are provided with semi-circular flanged apertures and secured together at said flanges with the apertures in aligned relation to 30 form a circular outwardly flanged opening, and like pot-shaped reinforcing members having ring portions which extend laterally beyond the bulge of the barrel and portions which extend beyond the ends of the barrel, which members are press 35 fitted and secured to the elements.

2. A barrel made of two pairs of like stampings, the elements of either pair being formed exactly alike, at least one pair of said elements having a semi-circular aperture at their marginal edges, flanges integrally formed on each of said elements about said semi-circular aperture, said apertures forming a circular outwardly flanged opening at the bilge of the barrel when the stampings are united to form the complete barrel, and a ring carried on the outside of said flange and forming therewith a bung ring.

3. A liquid-containing portion of a barrel made of like metal stampings having outwardly projecting flanges and a flanged semi-cylindrical aperture in continuation of said first flange, said stampings being oppositely disposed and welded together with the apertures in aligned relation to form a circular outwardly flanged opening, and a bung ring surrounding the flange of said opening and welded thereto.

4. A liquid-containing portion of a barrel made of two like stampings having semi-circular apertures, which stampings are oppositely disposed and joined together to have the apertures form a circular opening, and like pot-shaped reinforcing stampings having edge portions press fitted over said first stampings to have portions substantially spaced therefrom.

CHARLES H. WIDMAN.
